UNITED STATES PATENT OFFICE

FRANK S. SCHADE, OF HOLYOKE, MASSACHUSETTS, ASSIGNOR TO NATIONAL BLANK BOOK COMPANY, OF HOLYOKE, MASSACHUSETTS, A CORPORATION OF MASSACHUSETTS

LOOSE LEAF BOOK

Application filed May 19, 1931. Serial No. 538,477.

This invention relates to loose leaf books. Its object is to provide an improved structural arrangement of leveling pads for use in a book having sets or banks of overlapping record sheets with division sheets between each bank, and which need pads to give the entire book filler a substantially uniform thickness. The improvement is in the character of the pad and in the character of the arrangement of the pads with the sheets in the book.

To illustrate my invention in a preferred form and in some alternative forms, reference is made to the accompanying drawings and description:

Fig. 1 is a plan view of one set or bank of overlapping sheets, called record sheets, such as may lie between two index or dividing sheets in a loose leaf binder;

Fig. 2 is an edge view of the bank of overlapping sheets of Fig. 1 with the sheets slightly separated to more clearly show their arrangement, whereas such sheets are normally not thus separated in the book but lie directly in contact with one another;

Figs. 3 and 4 show a pair of the improved leveling pads in their preferred form and in the arrangement where the pad of Fig. 3 would lie against the back of a set of record sheets at the top and the pad of Fig. 4 would lie against the same set of record sheets at the bottom in a loose leaf book containing my invention;

Fig. 3a shows edge views of a series of my leveling pads to indicate that the pads of Fig. 3 alternate in arrangement with the pads of Fig. 4 at the top of the book, it being understood that a set of record sheets will lie between each successive pair of such pads;

Fig. 4a is a view similar to Fig. 3a to indicate that the pads of Fig. 4 also alternate in arrangement with the pads of Fig. 3 at the bottom of the book. These views in Figs. 3a and 4a indicate the series and alternate arrangement of the pads of Figs. 3 and 4 at the top and bottom of a loose leaf book according to the preferred form of my invention;

Fig. 5 shows an edge view of part of a loose leaf book arranged vertically, contain-

ing dividing sheets, leveling pads, and many banks of the record sheets such as shown in Figs. 1 and 2. In this Fig. 5, a portion of the book filler sheets are shown slightly separated to better indicate the arrangement 55 of parts according to my invention;

Fig. 6 is a view of Fig. 5 with the book laid on its side to indicate the front edge and how the filler sheets with the leveling pads square up with uniform thickness; 60

Figs. 7 and 8 are views of one and the same dividing sheet but on opposite sides and showing a modified arrangement of the leveling pads arranged so as to be carried by a dividing sheet; and 65

Fig. 9 shows perspective views of a pair of leveling pads such as may be used without any backing or carrying or dividing sheets.

I will describe the preferred form of the 70 invention shown in Figs. 1 to 6, but it should be understood that the arrangement I am about to describe is intended as illustrative and may be changed in some details without departing from the spirit of my invention. 75

The loose leaf book 1 as shown is of a well known type except in the character of the leveling pads and their arrangement in the book. The leaves of the book and the leveling pads are all provided with perforations 80 and are removably bound to the book by prongs at the back. Most of the leaves are arranged in separated banks, with a complete index or dividing leaf between adjacent banks. Each bank 3 is made up of 85 sheets over-lapped for title visibility, as shown in Figs. 1 and 2, and lie between dividing sheets 5, one of which is indicated in Fig. 1 at its outer edge. These overlapped sheets as a whole in each bank extend over the area of a dividing sheet 5. Individually each sheet of a bank is of less area than a dividing sheet. They are all of the same size, like a pack of cards, and are so overlapped that their edges show a visible title 90 for convenient identification. In this spread-out condition the thickness of each bank 3 varies, being greatest in the lateral middle portion and gradually tapering towards both the top and bottom edges of the 100

book to the thickness of one sheet, as will be clear from Fig. 2. I shall refer to this and any similar arrangement of sheets in a book which tapers toward one of more edges of the book as the record sheets. A complete covering sheet in the book on either side of such record sheets I shall refer to as a dividing sheet. This type of book is commonly arranged as I have described it with alternating banks of record and dividing sheets of desired book thickness. And due to the variable thickness between the center and ends of each bank of record sheets, various types of leveling pads have been proposed for squaring up such a book so as to make it of uniform thickness. This is important not only for the sake of a better appearance but more than that is the importance of a better writing surface as these books are opened up and used.

So far as I know, the leveling pads heretofore proposed are either expensive to make or of a character detrimental to the flexibility of the book, rendering it clumsy and awkward for the work of the user, or both expensive and clumsy. For these reasons the prior art leveling pads have gone into only limited use, although the books described are in wide use. As such books increase in thickness, the need for leveling pads is greatly emphasized, and when the leveling pads are expensively constructed the number needed increases the expense so much that I believe this is one of the reasons why they have not gone into general use.

Having these things in mind, I have developed a form of leveling pad structure which is comparatively inexpensive and which by its variable arrangement in the book compensates for variations in thickness of the banks of record sheets in an improved manner.

The structure in its preferred form is shown in Figs. 3, 3a, 4, and 4a. It consists of two pads *a* and *b* of slightly different construction. The pad *a* is made up of a backing sheet 9 and along the top edge a thicker sheet 11 is laid over sheet 9 to form a thick band extending from side to side but only part way down sheet 9. The pad *b* is made up like pad *a* except the thicker sheet 13 in this instance extends from the bottom edge of its backing sheet 9 upwardly to form a substantially wider band and thus cover more area than sheet 11 will cover. Sheets 11 and 13 are thus preferably of different area but of equal thickness. Otherwise the two pads *a* and *b* are the same. They each have perforations 15 along their binding edges and may be bound into the upper and lower ends of the book just as short sheets may be bound therein. One advantage of the backing sheet 9 being alike in both pads *a* and *b* is that the one with the narrow band will be bound in the book in the same way that the one with

the much wider band is bound. But this is a detail of the preferred form and not essential to the broadest aspect of the invention. By having equal and long enough binding edges, neither one will shift and go askew on the binding posts.

The inner longitudinal edges of pads *a* and *b* are conveniently arranged in the book to substantially coincide with the top and bottom lines of the area where the record sheets are overlapped with their maximum thickness. It is from the neighborhood of such lines up to the top and bottom edges of the book that one wants to compensate by the use of leveling pads for the tapering thickness of the banks of overlapping record sheets.

It will be seen that the pad *a* will compensate for this less than pad *b* because of the difference in areas of the thickened parts 11 and 13. Instead of attempting to make a pad that will exactly compensate for the taper of the record sheets, I have deliberately made pad *a*, which falls somewhat short of this ideal, and pad *b*, which goes somewhat beyond it. In this way I have taken a generous tolerance which is under in pad *a* and over in pad *b* the degree of thickening desired. The narrow thickening band is preferably half of the wider one, so the positive and negative tolerance is equal.

I have observed by actual experiment and practice that I can take a loose, leaf book made up of any number of banks of record sheets, determine the total amount of thickness required to level up the top and bottom edges of the book with its middle portion, divide such total by the number of banks of record sheets, make the thickness of my leveling pads at their thick portions equal to the divided amount and level the book in a perfectly satisfactory way by placing one pair of my leveling pads *a* and *b* adjacent each bank of record sheets. To do this it is necessary to have the pads *a* and *b* substantially alternate in their arrangement through the book so that, for example, substantially one-half of pads *a* will be in place at the top of the book and one-half at the bottom, and each half of pads *b* will be placed likewise. The orderly and preferred way to do it is to alternate the position of pads *a* and *b* from top to bottom of the book as they are placed adjacent successive banks of the record sheets. Of course the exact arrangement may be varied and still get substantially the same result if the purpose of alternating the position of the leveling pads and the idea of the invention are kept in mind.

While my description of the invention may suggest the need for estimating the amount of leveling necessary in this or that book and putting the user to the bother of doing a lot of work, the condition of the business does not in fact require this. The only thing the

user has to do is to buy the standardized record sheets and a number of pairs of leveling pads equal to the number of assembled banks in his loose leaf binder.

It may be a convenience in some instances to use the general dividing sheet 5 which is normally placed against each bank of record sheets as the backing or carrier for the leveling pads. In such a case, the backing sheets 9 would not be used. The dividing sheet 10 is always put in the book between each bank of record sheets. And so by attaching the thickening pads 11 and 13 directly to the dividing sheet 5, a narrow one on one end and a wide one on the other end, the arrangement 15 of leveling pads in the book would necessarily be made in accordance with my plan by merely alternating, end for end, the dividing sheets in their proper order. I have shown a preferred form of this modification 20 in Figs. 7 and 8. It will be noticed that I have put the thickening pads 11 and 13 on opposite ends and opposite sides of the dividing sheet.

In the use of the book with the leveling pads therein, it is desirable to have the pads 25 flexible. My preferred structure is made of paper or paper-like material, but of course other materials can be used such as fabric, leather, or leather substitutes, or other desired material.

When I make up my leveling pads, I prefer 30 to use paper and I prefer to attach backing sheet 9 to its thickening band 11 or 13 so the two parts move together. These two parts might be positioned in the book without mutual attachment by merely placing them on the binding posts or prongs, and the sheets 35 9 might even be omitted entirely, as I have indicated in Fig. 9. But as I stated, the backing sheet 9 is less likely to go askew in the book than a narrower band, such as 11, so the latter can be attached to its backing sheet 40 with advantage. It might be pasted over its whole area for attachment, but the preferred way, to increase flexibility of the pad, is to make a partial attachment, just enough so the two sheets of the pad will move together to 45 prevent the narrow one going askew. To do this a small margin at any one of the adjacent edges or two of them will be sufficient. I have found it satisfactory to attach the thickening bands 11 and 13 to their backing sheets 9 along two adjacent edges of the band, 50 as indicated in Figs. 3 and 4 by dotted lines to indicate the pasted portions. This construction permits the easy handling of the pads outside the book and a considerable amount of flexibility between the two in the 55 book.

The assembled book, as shown in Figs. 5 and 6, consists of the binder and, reading from one side of the book to the other, one arrangement of sheets would be as follows: 60 a blank title page 17 like the dividing sheet,

a dividing sheet 5, a bank of record sheets 3, a pair of leveling pads with the backing sheet facing the bank of record sheets, another dividing sheet, another bank of record sheets, another pair of leveling pads with the 70 backing sheet facing the bank of record sheets but reversed in arrangement with respect to the preceding pair of pads, another dividing sheet, etc., throughout the thickness of the book.

The user of such a book will find it of substantial uniform thickness over all. When he turns to any bank of record sheets and starts to write on either side of such sheets he will find a good writing support from the uniform thickness of the book, and this will be improved in the preferred form because each sheet will be backed up by either the smooth backing sheet of a pad or an adjacent dividing sheet. The backing sheet or the dividing sheet lies between the record sheets and the leveling pad. Thus when the writing comes to the edge of the thickening band of the pad, the shoulder at that edge will be substantially obliterated or bridged by the intervening sheet, giving a good writing support. And the thickness of the book from the writing surface to the cover is made substantially as level overall as an ordinary writing book by reason of the separated and alternating arrangement of leveling pads.

I have described my structure in its preferred form and with a few modifications, and I desire to claim it as completely as the prior art permits.

What I claim is:

1. In combination with overlapping record sheets and dividing leaves for loose leaf books, pairs of leveling pads composed of sheets of paper-like material having holes along one edge thereof, each sheet having attached thereto a strip of flexible material, the width of one varying from the width of the other in each pair, the pads being assembled within the book so that the varying widths alternate and thus provide a substantially uniform thickness to the assembled filler.

2. An assembly of sheets for use in loose leaf books comprising in combination banks of overlapped record sheets, each bank being in thicker arrangement approaching the middle portion than it is approaching the top and bottom edges, and sets of leveling pads each set of pads being made up of one part that will give more and one that will give less than a compensating thickness for the loss of thickness between the middle portion and one of said edges of a bank of record sheets, said sets of leveling pads being arranged for alternating positions between individual banks of record sheets so that the error in said over-compensating for thickness in the use of some pads will be corrected by the under-compensating for thickness in the use of the other

pads and the assembly will be of substantially uniform thickness.

3. A pair of leveling pads comprising two separated portions for use one above and one below the middle portion of a bank of overlapping record sheets, said portions being of uniform length and thickness but one having substantially double the area of the other, and means to bind the pads in a loose leaf book.

4. In combination, a bank of overlapped sheets tapering in thickness from the middle portion toward each of two opposite edges, a pair of leveling pads one having substantially twice the area of the other, one arranged to over-compensate and one arranged to under-compensate for said taper when placed at opposite sides of said middle portion of the bank, a second bank of said sheets and a second pair of said leveling pads, the latter being arranged over its sheets in the reverse arrangement to that of the first pair over its sheets so that when the whole combination is assembled in a pack the latter will be of substantially uniform thickness.

5. A loose leaf book comprising in combination a cover having loose leaf binding means, a multiplicity of banks of overlapping visible index record sheets, dividing sheets separating such banks, leveling pads consisting of two separated backing sheets of substantially equal area and on said backing sheets thickening sheets, one of the latter being substantially twice the area of the other and extending inwardly from the top and bottom edges of the book, said dividing sheets or said backing sheets being arranged to overlie said thickening sheet as the record sheets are used, said sets of leveling pads being arranged in alternating order in the book so that the areas of the thickening sheets will be substantially equal in the upper and lower portions of the book and the book will be of substantially uniform thickness.

6. In combination with overlapping record sheets and dividing leaves for loose leaf books, pairs of flexible pads of uniform thickness, but one of greater area than the other, arranged between the banks of record sheets and dividing sheets and in alternating relation to the adjacent pair of pads.

7. In combination with overlapping record sheets and dividing leaves for loose leaf books, sets of wide and narrow leveling pads made of flexible material of uniform thickness throughout, said pads being arranged between the dividing leaves and banks of record sheets in approximately equal number of each at both upper and lower ends of the filler.

In testimony whereof I have affixed my signature.

FRANK S. SCHADE.
